VACUUM CLEANER HOSE HANDLE

Raymond Descarries, Montreal, Quebec, Canada, assignor
to Consolidated Foods Corporation, Old Greenwich,
Conn., a corporation of Maryland

Filed Sept. 30, 1968, Ser. No. 13,781

Term of patent 14 years

Int. Cl. D15—07

U.S. Cl. D49—17.2

FIG. 1 is a side elevational view of a vacuum cleaner hose handle according to my new design.

FIG. 2 is a top plan view thereof.

FIG. 3 is a bottom plan view thereof.

FIG. 4 is an end view thereof looking at the left end as shown in FIG. 1; and

FIG. 5 is an end view thereof looking at the right end as shown in FIG. 1.

The broken lines shown in FIGS. 1, 2 and 3 are for illustrative purposes only.

I claim:

The ornamental design of a vacuum cleaner hose handle, as shown and described.
